C. J. AND G. J. CLEFTON.
GAS GENERATOR.
APPLICATION FILED JUNE 11, 1917

1,417,974.

Patented May 30, 1922.

UNITED STATES PATENT OFFICE.

CLAUD J. CLEFTON AND GUY J. CLEFTON, OF OWATONNA, MINNESOTA.

GAS GENERATOR.

1,417,974.

Specification of Letters Patent. Patented May 30, 1922.

Application filed June 11, 1917. Serial No. 174,050.

To all whom it may concern:

Be it known that we, CLAUD J. CLEFTON and GUY J. CLEFTON, citizens of the United States, residents of Owatonna, county of 5 Steele, State of Minnesota, have invented certain new and useful Improvements in Gas Generators, of which the following is a specification.

In the operation of an acetylene lighting plant, difficulty is sometimes experienced in 10 using the lights after the generator has been opened for any purpose, such as supplying fresh carbide thereto, owing to the fact that as ordinarily constructed a considerable 15 quantity of air will be admitted to the tank and will mix with the gas to such an extent that the illuminating flame at the burner will be dim and unsatisfactory.

To this end our invention consists generally in providing a gas generating tank 20 equipped with the means for excluding entirely when desired the entrance of air therein.

In the accompanying drawing forming 25 part of this specification,

The figure is a vertical sectional view through a gas generator embodying our invention.

In the drawing, 2 represents the generating tank, which, as usual in apparatus of 30 this kind, is buried in the ground. 3 is a cover for the tank, removable for access thereto, as when the apparatus is to be supplied with carbide. In the bottom of the 35 tank is a water chamber 4. Within the tank is a sleeve 5 having flaring lower walls 6 secured at 7 to the walls of the tank. In the top of this sleeve is a carbide hopper 8 having valves 9 for regulating the discharge of 40 carbide from the hopper. The hopper has a closed top 10 and a lever device 11 is mounted on said top and connected by a rod 12 with the valve 9 for regulating the movement of the same as the gas bell rises and 45 falls. This apparatus is substantially as shown, described and claimed in U. S. Patent No. 1,133,618, issued March 30, 1915, and we therefore make no claim to the same in detail herein.

50 The annular space between the sleeve 5 and the wall of the tank forms a gas bell chamber in which a supply of water or oil is placed, and the lower end of a gas bell 14 is submerged in this liquid while the upper 55 portion of the bell encloses and covers the carbide hopper and the upper part of the

sleeve. This chamber, as shown clearly in the drawing, is entirely independent, as far as the liquid therein is concerned, of the generating chamber, and the liquid remains 60 in this gas bell chamber permanently and is not affected in any way when the water is removed from the chamber 4. A perfect seal is therefore provided against the entrance of air around the gas bell. The bell 65 is mounted to rise and fall in the tank, as usual in devices of this kind, and the tank wall has guide rails 15 to receive arms 16 mounted on the gas bell. A series of ports 17 are provided in the wall of the sleeve 5 70 leading from the water chamber or the gas generating space to the space in the upper part of the gas bell. As the pressure of the gas increases, the bell will rise and the weighted lever 11 will automatically shut off 75 the feed of carbide, and as the pressure of the gas decreases, the bell will drop and operate the lever 11 to open the feed valve and resume the feed of carbide. This is all described in detail in the previous patent, 80 above referred to.

For the purpose of filling the carbide hopper, the gas bell is provided with an opening in the top thereof and a sleeve 18 is fitted into said opening and extends above 85 and below the same, and a shorter sleeve 19 is mounted on the underside of the top of the bell and encircles the lower portion of the sleeve and is spaced therefrom and telescopes with a similar sleeve 20 that is mounted on the top of the carbide hopper. Within the sleeve 18 is a can 21 having a valve seat 22 at its lower end and a valve 23 provided with an operating rod 24. A cover 25 is provided for the sleeve 18, held in place by a clamp 26, and when this cover is removed the spout of the filling can may be inserted into the can 21 for the purpose of filling the carbide hopper. The can 21 serves as an auxiliary supply by means of 90 which the user of the apparatus, by opening the valve 23, can admit sufficient carbide to the hopper beneath and the generating tank to carry the apparatus through the night, as it might happen sometime that the carbide 95 in the hopper would become exhausted early in the evening, when it would be awkward or inconvenient to remove the cover and refill the hopper. In such case it would be only necessary to open the cover and raise 100 the valve 23, when sufficient carbide would be delivered to run the system for several 105 110

hours. This feature of the machine is also shown and described in Patent No. 1,133,617, issued March 30, 1915.

The top of the carbide hopper is provided with a filter 27 having holes 28 for the admission of gas and a pipe 29 leads from the filter to the service pipe 30 on the outside of the generator. This pipe extends vertically to the top of the ground and has a branch 31 leading off to the lighting system and is provided with a valve 32 having an operating rod 33 by means of which the gas may be cut off entirely from the system whenever desired. An upright pipe 34 is provided on the outside of the generator and adjacent thereto and has a connection at its upper end for a pump by means of which the sludge or residuum of the carbide may be pumped out from the generating tank. This connection consists preferably of a coupling 35 mounted on the end of the pipe 34 and having a plug 35' fitting therein.

We prefer to provide a rod 36 within this pipe having at its lower end an agitating blade 37 which projects through an opening 38 in the wall of the tank in position to sweep over a portion of the inclined floor 39 of the generating tank and so stir up and agitate the sludge and mix it with the water that it can be readily pumped out of the tank.

We prefer also to provide a wall 40 depending below the lower end of the pipe 34 and co-operating with a casing 41 which encloses the lower portion of the pipe to form a water seal which normally closes the pipe 34 against the entrance of air therethrough into the tank. On the opposite side of the machine is a similar pipe 42, having a rod 43 therein provided with an operating handle 44 at its upper end and an agitator or scraper 45 at its lower end, a casing 46 being provided to encircle the lower portion of the pipe and having a wall 47 co-operating therewith to form a second water seal and prevent the entrance of air into the generator. This feature of the water seals in the bottom of the generator and the general provision for preventing the admission of air to the generator we regard as the important part of the present invention, as we are able to exclude air from the generating tank when the cover is removed and fresh carbide is being placed in the machine, and also prevent the entrance of air when the sludge is being pumped out.

We prefer to arrange the trap or seal for the pump pipe about three inches above the bottom of the tank, so that there will be approximately three inches of water left in the tank during the pumping operation. This is for the purpose of submerging any carbide which may be spilled in the tank while the generator is being recharged and when the operator carelessly admits air to

the chamber. We have found that where the tank is drained dry and then fresh carbide falls upon the wet surface and the scraper blade is operated back and forth over the carbide, it might become sufficiently hot to create a spark and with air in the tank, a resulting explosion. This danger is entirely eliminated by leaving a small quantity of water in the bottom of the tank.

We will now describe the operation of recharging the generator. We will assume that all the carbide in the hoppers has been used and that we are about to remove the water from the chamber and clean out the apparatus preparatory to placing a fresh charge of carbide therein. We first remove the cover 3 and take out the auxiliary carbide holder and refill it, then insert the filling tube and recharge the carbide hopper or holder. We then replace the auxiliary carbide holder and to start the feed find it necessary to raise the gas bell some three or four inches. This is necessary, as when the carbide holder is empty the gas bell will drop and rest upon the lever device 11 and because of the double construction of the valve in order to again put the feed and control devices 9 and 11 in operation, it is necessary to lift the gas bell and permit these devices to assume the proper position for depositing carbide in the water and then to allow the bell to drop to actuate the valve to deposit a quantity of carbide in the generator.

When the above described steps have been taken, we then remove the bushing 35' and attach a pump by suitable means to the coupling 35 and begin to pump the water and sludge out of the chamber 4. Before pumping out the water and sludge, we operate the 105 agitating device thoroughly to stir up the sludge which has accumulated in the bottom of the water tank. We are particular to operate the agitator 37 before the pump is attached to the pipe 34, for the reason that there will be no opportunity to operate it when the pump is in use. The agitator on the other side of the tank is operated from time to time, as may be necessary during the process of removing the water and sludge from the chamber. The removal of the water and sludge will cause the gas bell which has been elevated by the generated gas to drop and connect with the lever device 11 again and deposit a certain quantity of carbide in the water which still remains in the generating chamber 4 and this carbide so deposited will immediately make gas which will rise, following the course indicated by the arrows, and upon entering the gas bell 125 will lift it out of contact with the lever device. This operation will continue during the entire process of removing water from the generating chamber and as fast as water is removed from the generating chamber, 130

the space occupied thereby is immediately filled by the pure gas generated during the water-removing operation.

We have now pumped all the water from the chamber 4, which has been entirely filled with pure gas, and it has been unnecessary to admit air to take the place of the water pumped out and no vacuum is formed, as the generating gas immediately fills the space in the tank left by the removal of the water. It will be readily understood that the pumping out of the water and sludge from the generating chamber acts upon the gas bell and feeding device in the same way as the drawing of gas through the pipe 30, and will cause the feeding of the carbide and the generation of gas during the entire process of pumping out the water and sludge from the chamber 4.

Assuming now that all the water and sludge has been removed from the chamber 4, the traps 41 and 46 filled with water will prevent the escape of pure gas from the generating chamber or any part of the generator containing such gas above this chamber, and these traps not only prevent the escape of gas when the water and sludge has been removed, but also positively prevent air from entering the generating chamber at such a time.

In the top of the gas bell we provide a cap or cover 48 mounted on the upper end of a small pipe 48' which projects through the top of the gas bell and extends down into the liquid seal in the gas bell chamber to a point near the lower end of the bell. The cap prevents any foreign material from dropping into the open upper end of the pipe but is spaced from the pipe and from the top of the gas bell to allow the escape of pure gas which may enter the open lower end of the pipe and pass up through the top of the bell when it rises in its liquid seal to a predetermined point. The upper end of the pipe and the housing will be sufficiently above the top of the gas bell to prevent any water from entering the pipe and running down into the gas bell chamber. This pipe is used purely for the escape of surplus gas when the water chamber is being refilled and has no other function except that under certain conditions it will act as a relief or escape for any overplus of gas which may have accumulated in the generator.

A water pipe 49 is provided adjacent the pipe 42 and connected therewith by the coupling 50 so that water may flow down through the pipe 49 and from the pipe 42 into the base of the generator. This pipe 49 provides a convenient means for delivering water to the generator and controlling such delivery automatically without disturbing any other parts or connections.

To refill the generating chamber with water we remove the cover to the can 54 and allow

water to flow therein until the float 51 closes the valve 53, at which time there will be a proper level of water in the generating chamber. During the refilling of the tank, the gas bell will rise as the water level rises in the water chamber until the open lower end of the relief pipe is sufficiently near the surface of the gas chamber seal to allow surplus gas to escape through it and through the top of the gas bell into the open air. This will continue during the entire period of filling the water chamber. When the chamber is filled, the gas bell will resume its usual position and the relief pipe inlet will be sealed against the escape of gas within the gas bell chamber.

When the operator removes the auxiliary holder 21 to recharge or refill the auxiliary hopper as well as the main carbide holder, the top of the gas bell will rest upon the standard of the feed device 11 and make a practically tight joint with the upper end of the sleeve 20 that is mounted on the top of the carbide holder. The empty carbide holder will fill with pure gas and when the operator inserts the filling funnel to pour carbide into the main carbide holder, the pure gas will be driven out and its place taken by the fresh carbide and the escape of gas from the holder will tend to drive back any air which might otherwise enter and the contact of the gas bell with the top of the telescoping section of the auxiliary carbide holder will prevent any air from working into the bell when the auxiliary hopper is removed. We are thus able to thoroughly exclude air from the generator—first, while the auxiliary carbide holder and the main holder are being refilled, then during the operation of removing the sludge and water from the generating tank, and during the refilling of the tank with fresh water. The entrance of air into the lighting system is thus positively prevented throughout all the steps of charging the generator with carbide, removing the water and sludge and refilling the generating tank. All danger of explosion incidental to the cleaning and recharging of an acetylene generator tank is thereby positively eliminated.

We prefer to provide a check valve 29' in the pipe 29. If the operator in recharging the generator becomes careless or undertakes to perform the operation without closing the valve 32 leading to the burners, or if he should neglect to put carbide in the holder and start the machine but should immediately begin pumping without making any provision for supplying the place of the water pumped out, and assuming that there are some burners open in the system, the generator would begin to take air through these burners and the pipe 29, but the entrance of air into the generator would be prevented by the check valve, which would

rise and seat itself on the seat provided in the pipe and positively prevent any entrance of air into the generator from the system through the pipe 29.

5. We claim as our invention:

1. A method of removing sludge from a deflated acetylene gas generator to the exclusion of air, comprising feeding carbide to the generator hooper to the exclusion of air, 10 lifting the bell of the container and allowing it to fall to admit a small quantity of carbide to generate sufficient gas within the generator to fill the space left by the removal of the sludge, and removing the sludge from 15 a point below the operating level of liquid within the generator, as described.
2. An acetylene gas generator having means for emptying the water from the same without admission of air to the generator comprising a generating tank, a sleeve, 20 a bell over the sleeve, a fluid seal at the bottom of the bell and sleeve, a hopper closing the end of the sleeve, a port or second hopper having walls to shut out air from the space between the bell and sleeve tops, means for depositing carbide from the first 25 hopper by raising and lowering the bell to generate gas and a pressure in the tank whereby entrance of air into the tank when the water is removed is prevented, and a 30 discharge pipe leading from near the bottom of the tank through which the water and sludge may be removed from the generating tank and whereby a water seal is 35 formed between the pipe and tank to prevent air entering the tank from said pipe at the end of the sludge removing operation.
3. An acetylene generator comprising a 40 tank having a water inlet port and a sludge outlet port arranged on the opposite sides of the tank, a casing for each port having

a depressed wall providing a chamber, a pipe rising from each casing, and a baffle depending within each casing into the chamber thereof to a plane below the adjacent port and between the latter and the adjacent pipe. 45

4. An acetylene generator comprising a tank having a water inlet port and a sludge 50 outlet port arranged on the opposite sides of the tank with the outlet port in a higher plane than the inlet port, the bottom of the tank inclining downwardly from the inlet port toward and beneath the outlet port, 55 a casing for each port having a depressed wall providing a chamber, a pipe rising from each casing, a shaft journaled in each pipe, a long arm fixed to the lower end of the shaft in the inlet pipe and extending inwardly over the bottom and a comparatively short arm fixed to the shaft in the outlet pipe and extending down and over the lower edge of the bottom of the tank to cooperate with the first arm in agitating the sludge. 60 65

5. An acetylene gas generator comprising a generating tank, a hopper for feeding carbide thereto, a discharge pipe through which the water and sludge may be pumped from the generating tank, a rod extending through 70 the pipe and having a stirrer thereon extending into the generating tank, and a water seal between the pipe and tank to prevent air entering the tank from said pipe at the end of the pumping operation 75 as described.

In witness whereof, we have hereunto set our hands this 4th day of June 1917.
